UNITED STATES PATENT OFFICE.

DAVID HEYMAN, OF NEW YORK, N. Y.

TOY CASH-REGISTER.

1,141,547.

Specification of Letters Patent.

Patented June 1, 1915.

Application filed December 17, 1914. Serial No. 877,691.

To all whom it may concern:

Be it known that I, DAVID HEYMAN, a citizen of the United States of America, residing at New York city, in the county and State of New York, have invented certain new and useful Improvements in Toy Cash-Registers, of which the following is a specification.

My invention relates to toy cash registers. 10 The object of the invention is to provide a simply constructed toy, of neat appearance, closely simulating the appearance of the operative full sized cash registers at present employed.

15 A preferred embodiment of the invention is illustratively exemplified in the accompanying drawing, in which—

Figure 1 is a front elevational view of the device; Fig. 2 is a vertical sectional view 20 thereof on the line 2—2 of Fig. 1; and Fig. 3 is a fragmentary sectional view on the line 3—3 of Fig. 2.

25 Referring to the drawing by reference characters, 10 denotes generally the casing of the register, this casing closely resembling in shape that of a full sized cash register.

30 Traversing the lower part of the casing is a rock plate 11 capable of rocking on pivots 12 which project from the sides of said plate 30 and enter orifices 12^a in the opposite sides of the casing 10. The rock plate carries a pair of depending stops or abutments 13 which are adapted to normally retain the cash drawer 14 within the casing 10. The cash 35 drawer is slideable on the base of the casing 10 and is adapted to be moved out of the casing by a pair of coiled springs 15, having their ends attached respectively to the rear of the drawer 14 and to the front wall of 40 the casing 10. The front wall of the drawer is of sufficient width (Fig. 2) to overlap the edges of an aperture 16 in the front wall of the casing 10 through which the drawer may be protracted by the springs 15.

45 Secured within the casing 10 and depending from the top wall thereof is a substantially triangular bracket comprising the vertical wall 17, the horizontal wall 18 and a vertical upwardly directed flange or ledge 17^a. The horizontal wall 18, immediately adjacent the wall 17 is slotted to receive the indicating bars each of which comprises the elongated substantially vertical member 19 and the hook shaped lower end 20 designed 50 to take under the rear edge of the rocking plate 11. Each indicating plate is provided

near its upper end with a suitable number 21 corresponding to the value of a coin inserted in the cash drawer and adapted to be indicated by such indicating plate. The indicating plates are movable through openings 22 formed in the upper curved wall of the casing 10.

55 Supported by the flange 17^a is a series of keys or levers 23 having numbers thereon corresponding with the numbers on the indicating plates 19. Each of the keys 23 has a depending forked portion 24 which straddles the flange 17^a, and a rearwardly extending arm which passes through a slot 26 in 70 the indicating plates 17, and a slot 27 in the wall 17 of the bracket. The front portion of the upper curved wall of the casing 10 is also provided with a series of elongated slots 28 in each one of which one of the keys 23 75 may be reciprocated.

80 The rocking plate 11 is normally kept in substantially horizontal position by a spring 29, one end of said spring being held in a socket 29^a on the plate 11, and the other end of the spring impinging against the under face of the wall 18.

85 In the drawing the toy cash register is shown as comprising five keys 23 and as many indicating plates. Ordinarily the device will contain this number of keys and plates, but it is to be understood that I may use a greater or less number of keys and plates if found desirable. The device is adapted to receive coins of different denomination, the keys respectively bearing the 90 numbers which correspond to the denominations of the coins to be received, and the indicating plates which are apportioned to the keys also being provided with numbers corresponding to such keys.

95 The operation of the invention will be understood from the following description: Let it be assumed that a twenty-five cent piece is to be inserted in the cash drawer 14. 100 The right hand key, bearing the notation "25," will be depressed causing it to oscillate about the flange 19 and assume the position indicated in dotted lines in Fig. 2. As a result of this movement, the rearwardly extending arm 25 will raise the corresponding indicating plate 19 so that its lower hooked end 20 will be moved upwardly to cant the plate 11 into the dotted position, thus moving the stops 13 out of the path of the rear 110 wall of the drawer 14 and permitting the springs 15 to pull the drawer outwardly into

the dotted position indicated. By raising the plate 17, its upper portion projects beyond the upper wall of the casing, disclosing a number which indicates the value of the 5 coin inserted in the register. After the coin has been inserted, the drawer is pushed inwardly and if pressure on the key 23 has been removed before the drawer itself is pushed back into casing 10, the drawer will 10 in moving backwardly ride on the curved faces of the stops 13 thus moving these stops out of the way of the retracted drawer. After the drawer has passed the rear straight edge of the stops 13 the latter will be forced 15 into the locking position by means of the spring 29.

It will be understood that the plate 11 is common to all the indicating plates 19, the latter being capable of individually operating said plate.

What I claim is:—

1. In a toy cash register, the combination of a casing, a bracket supported therein, keys pivotally mounted on said bracket, indicating plates slidable in said casing and having slots through which portions of said 25 keys pass, each of said indicating plates hav-

ing a hook formed at its lower end, a rocking plate having its rear edge projecting over the hooked ends of said indicating plates, a drawer slideable under said rocking plate, stops on said rocking plate and engageable with said drawer to retain the latter in the casing, and means for protracting said drawer when released from said stops. 35

2. A toy cash register, comprising a casing a rocking plate mounted in said casing, a drawer slideable on the base of the casing under said rocking plate, stops depending from said rocking plate into the path of said 40 drawer to lock the same in the casing, means for normally maintaining said rocking plate in a substantially horizontal position, a series of keys pivotally mounted within said casing, and a series of indicating plates in 45 operative engagement with said keys and having hooked ends adapted to engage and tilt said rocking plate.

In testimony whereof I have affixed my signature in presence of two witnesses.

DAVID HEYMAN.

Witnesses:

CLARICE FRANCK,
OTTO MUNK.
